HEAT TREATING FURNACE

Kenneth A. Stevenson, San Diego, Calif.

Application February 16, 1938, Serial No. 190,750

2 Claims. (Cl. 266—4)

(Granted under the act of March 3, 1883, as
amended April 30, 1928; 370 O. G. 757)

This invention relates to a heat treating furnace, and has for an object to provide an improved heat treating furnace especially suitable for heat treatment of high tensile aluminum alloys, as well as duraluminum.

In the heat treatment of duraluminum there are three very important factors necessary to the optimum success. These factors are accurate control of the temperature, uniform temperature throughout the furnace and rapid cooling from the heat treatment temperature so as to obtain maximum resistance to corrosion and tensile strength of the product.

The furnace of this invention is especially intended for use in heat treating duraluminum rivets, but of course is equally usable for heat treating other aluminum alloy products which are of a size that they may be conveniently placed in the furnace. One of the advantages of this furnace is a closer temperature control than previously possible. Although salt is used as a heating medium, it does not come into actual contact with the products being treated, and it is therefore not necessary to drain off the salt when the heating is stopped and the quenching takes place. The quenching is therefore more rapid and more effective, and the results are more accurate.

With the foregoing and other objects in view, the invention consists in the construction, combination and arrangement of parts as herein-after described and illustrated in the drawing, in which:

Figure 1 is a front elevational view of the furnace of this invention; and

Fig. 2 is a sectional view on line 2—2 of Fig. 1.

There is shown at 10 the furnace of this invention mounted on supporting legs 11 including sheet metal walls 12 and a removable cover 13. Within the walls 12 there is provided refractory fire brick 14, within which is supported a chamber 15. Extending into the bottom of this chamber 15 is a pair of electrical heating elements 16 receiving their current supply from conductors 17 connected at 18 to any suitable source of electricity. The front wall 19 is provided with insulation material 20, which insulation material 20 is likewise provided in the top cover 13. Extending through the front wall 19 and into the chamber 15 are a plurality of cylindrical tubes 21, seven being shown in this instance, these tubes 21 being made of metal or other good heat conducting material.

A supply of salt 22 placed in chamber 15 entirely surrounds the cylindrical tubes 21 and

serves as a heat conductor for transmitting the heat supplied by the electrical heating elements 16 to the tubes 21 and to cylinder drawers 23 which are placed therein. A thermo-couple 24 extends into the salt 22 within the chamber 15 for measuring the temperature and may be connected to automatic controls for regulating the temperature.

The drawers 23, as shown, are provided with handle pulls 25, which, it will be observed, extend in a set direction, showing that the drawer is in proper position for containing the duraluminum rivets or other products 26 within the semi-cylindrical drawer portion 27 thereof, and insulated portion 28 filled with the same insulation material 20 connects the same cylindrical drawer portion 27 to the handle pull 25.

The furnace 10 may be provided with any convenient number of drawers, the drawers shown being placed in two rows in staggered relation to each other, it being apparent that different products or different sized rivets may be placed in each of these drawers for simultaneous heat treatment. At the expiration of the heating period the drawers will be rotated 180° before they are withdrawn.

A quench tank 29 which may be filled with a cooling medium such as water, has a supply pipe 30 and control valve 31 at one end thereof, and an overflow drain and pipe 32 at the other end thereof, the quench tank 29 being supported at the front of the furnace 10 by braces 33 just below the mouth of the cylindrical tubes 21.

A foraminous cup 34, supported by a flange 35 through an opening in a plate 36, extends into the quenching medium in the tank 29, a removable funnel 37 being provided for the cup 34 located directly beneath the mouth of the tube 21, there being one cup and funnel for each tube.

In operation, the alloys or other products 26 to be heat treated are placed in the drawers 23 and inserted into the tubes 21, chamber 15 being filled with salt. The current is turned on and the temperature is controlled according to the temperature indicated by the thermo-couple 24. The salt liquefies and transmits a uniform degree of heat through the tubes 21 to the products 26 within the drawer portion 27. When the heating has been continued for the predetermined period necessary, the drawers are rotated and withdrawn, spilling the products 26 through the funnel 27 into the foraminous cup 34 within the quench tank 29. As a result of such construction there is no salt in actual contact with the products 26, and hence it is not necessary to drain

the salt off the products or rinse the products
26 before they are placed in the quench, and
there is no salt present to retard the speed of
the quench. The products may be removed from
5 exposure to the heat of the furnace to the for-
aminous cup within the quench in a period of less
than two seconds, thus preventing the loss of heat
between the furnace and the quench, which loss
of heat tends to destroy some of the corrosion re-
10 sistance, and to lower the tensile strength of the
product.

Other modifications and changes in the proportions
and arrangements of the parts may be made
15 by those skilled in the art without departing
from the nature of the invention, within the
scope of what is hereinafter claimed.

The invention described herein may be man-
ufactured and used by or for the Government
20 of the United States of America for govern-
mental purposes without the payment of any
royalties thereon or therefor.

Having thus set forth and disclosed the nature
of this invention, what is claimed is:

1. As an article of manufacture, a heat treat-
25 ment furnace comprising a heating chamber, a
heat source for said chamber, a tubular heating
chamber extending into said heating chamber
from one side thereof, a fusible salt within said
30 heating chamber encompassing said tubular
heating chamber and transmitting heat from said
heat source to said tubular heating chamber, a
product-container tubular insert extendable into
35 and retractable from said tubular heating cham-
ber, said insert being open on one side thereof
to receive or discharge products to be heat treat-
ed therein, said tubular heating chamber prevent-
ing the fusible salt from contacting the
40 products, handle means on said insert without
said heating chamber for rotating and with-
drawing said insert, said insert being rotatable
to discharge the products therein through the
open side, a quench means immediately without
said furnace below the path of said insert, said

quench means including a quench tank, and
means extending into said quench tank for re-
ceiving the products discharged from the open
5 sides of said insert and exposing the products to
the quenching effects of the quench tank, where-
by said insert may be rotated and retracted to
quickly remove the products from the heating
chamber to the quench tank in less than two
seconds.

2. As a new article of manufacture, means for 10
heat treating small aluminum alloy products at
a uniform temperature for a desired period of
time and for removing the heat treated products
from the heat treatment to a quench means within
15 a period of less than two seconds to minimize
loss of corrosion resistance, said means comprising
a comparatively large heating chamber, a
heat source within said chamber, a compara-
tively small unperforated tubular heating cham-
20 ber extending into said large heating chamber
from one side thereof, said large heating cham-
ber containing a fusible salt encompassing said
small tubular heating chamber for transmitting
heat from said heat source to said small tubular
25 heating chamber, said small tubular heating
chamber excluding said fusible salt from the in-
side thereof, a product-container tubular insert
extendable into and retractable from said small
tubular heating chamber, said insert being open
30 on at least one side thereof to receive or dis-
charge the aluminum alloy products to be heat
treated therein free from contact with the fusible
salt, means on said tubular insert for withdraw-
ing and rotating said insert to discharge the
35 products therein through the open side, and
quench means immediately without said heating
chamber and below the path of said tubular in-
sert as it is retracted whereby said insert may be
retracted and rotated to quickly remove the
40 products from the heating chamber to the quench
means.

KENNETH A. STEVENSON.
